UNITED STATES PATENT OFFICE.

CHARLES AMES ALDEN, OF STEELTON, PENNSYLVANIA.

RAILROAD FROG AND PROCESS OF MAKING SAME.

Application filed August 12, 1921. Serial No. 491,766.

To all whom it may concern:

Be it known that I, CHARLES AMES ALDEN, a citizen of the United States, residing at Steelton, Dauphin County, State of Pennsylvania, have invented certain new and useful Improvements in Railroad Frogs and Processes of Making Same, of which the following is a specification.

The present invention relates to railroad frogs and the process of making the same, and more specifically is directed to another species of the generic invention described and claimed in my application 384,237 filed May 25, 1920. It is also an improvement over the species described and claimed in my application 384,238 filed May 25, 1920.

Briefly stated the process described in said prior applications consists in forming the frog from a worked metal bar such as a rolled or forged bar. More specifically the process described in said applications consists in operating on a bar of substantially uniform cross sectional shape to widen the same approximately at the point where the wings are to end and forming the flangeways, wings and point.

The frog of the present invention has centrally disposed integral separator blocks at the ends thereof, to which the track rails are secured. Each block has its sides formed to snugly fit into the channels in the sides of the rails and is of gradually increasing width from its neck to its free end.

The frog described in said application 384,238 has similar separator blocks, but is made from a solid bar. The present improvement consists in forming the frog having separator blocks as described, from a bar with a groove in its bottom, extending from end to end thereof thus saving material as compared with manufacturing the same from a solid bar. In order that the blocks may not weaken too much, the groove is of less width than the necks of the separator blocks.

Other objects and features of novelty will be apparent from the description taken in connection with the drawings in which:

Fig. 1 is a top plan view of a bar or blank from which the frog is constructed;

Fig. 2 is a cross sectional elevation of the bar;

Fig. 3 is a plan view of the bar after the first operation has been performed on the same;

Fig. 4 is a sectional elevation taken substantially on the line 4—4 of Figure 3;

Fig. 5 is a sectional elevation taken substantially on the line 5—5 of Figure 3:

Fig. 6 is a top plan view of the completed frog;

Figs. 7 to 12 inclusive are sectional elevations taken on the corresponding section lines respectively of Figure 6; and

Fig. 13 is a perspective view of the frog shown in Figure 6.

According to the present invention the frog is constructed from a rolled, pressed or forged blank or bar of substantially uniform cross section, there being a narrow groove in the bottom of the bar extending from end to end thereof. As shown, the bar or blank 40 is of substantially uniform width and height and has the longitudinally extending groove 41 in its bottom face, this groove preferably not being much greater than a third of the width of the main part of the bar. At the lower edges of its longitudinal side faces, the blank may be provided with oppositely extending base flanges 42, the bottom surfaces of which are flush with the bottom of the bar. If the over all width of the bar is considered, the width of groove 41 should not be much greater than one-fifth thereof.

The first step of the process for forming the frog of the present invention consists in operating on the bar of Figure 1 to alter the cross sectional shape at a point intermediate the ends thereof. This operation is for the purpose of providing for the flanging of the wings at their ends and the increased width of the flangeways adjacent the ends of the wings. As shown in Figure 3, this operation consists in forming the two recesses 43 substantially triangular in plan view and spaced transversely of the top of the bar and further in forcing out the outer walls 44 bounding these recesses so that the bar is widened at this point. This may be accomplished by indenting the bar as by a rolling or pressing operation. The groove 41 at this region may be simultaneously widened and made deeper, as shown by the cross sectional view of Figure 5. This operation

may effect a slight elongation of the bar although the cross sectional area of the bar at the region adjacent the section line 5—5 of Figure 3 is maintained substantially the same as originally.

If desired, the work may be subjected to a suitable heat treatment at this stage of the process, for the purpose of raising the elastic limit and ultimate strength.

5 The next step in the process consists in operating on the top of the bar to form the flangeways 46, including the recesses 43. Preferably the flangeways are formed by removing metal from the top of the bar as 10 by machining, thus providing the opposite wings 48 and 49 corresponding to the wing rails of a frog and also providing the point 60 corresponding to the point rails. It will be noted that the ends of the wings are 15 flared outwardly as indicated at 50 and 51, and that the flangeways adjacent thereto are thus widened.

For the purpose of providing means for securing the track rails to the frog, the ends 20 are provided with the integral separator blocks 56 and 57. As clearly shown in Figures 6 and 13, these separator blocks are of increasing width from their necks to their outer ends. Their lateral sides are formed 25 to snugly fit in the channels in the sides of the track rails, as shown in Figures 7 and 12. The track rails are clamped against the sides of the blocks with their ends abutting shoulders 58 and 59 at the opposite ends 30 of the frog, suitable splice plates 60 and 61 being provided for this purpose. The splice plates fit in the outer sides of the rails and in channels or recesses 62 and 63 formed in the sides of the frog adjacent the necks of 35 the blocks. Suitable bolts 64 are provided and clamp the splice plates and rails to the frog.

As clearly shown in Figure 6, the groove 41 in the bottom of the frog is of less width 40 than the neck of the separator blocks. Preferably this groove is not substantially wider than one-third the width of the main part of the bar or blank.

Preferably the frog is constructed from 45 a worked steel bar, although the invention is not limited to this metal.

Although a specific frog and the process 50 of making the same have been described in detail, it is to be understood that the invention is not thus limited, but includes modifications and changes which come within the scope of the appended claims.

Having thus described the invention what is claimed as new and desired to be secured 55 by Letters Patent is:

1. As an article of manufacture a worked metal frog of substantially uniform cross sectional area throughout the greater part of its length having an integral separator 60 block at each end and adapted for securing

the track rails to the outer sides thereof, said sides being shaped to snugly fit into the channels in the sides of the rails, each block being of gradually increasing width from its neck to its end, and said frog having a groove in its bottom extending from end to end thereof. 65

2. The process of making a one piece railroad frog having an integral centrally projecting separator block at each end with its 70 sides shaped to snugly fit into the channels in the sides of the track rails, each block being of gradually increasing width from its neck to its end; consisting in operating on a bar of substantially uniform cross sectional shape having a groove in its bottom 75 extending from end to end, said groove being of substantially less width than the neck of the separator blocks, to widen the same at the regions where the wings are to end, 80 removing stock from the top of the bar to form the flangeways, wings and point, and operating on the end of the bar to form said separator blocks.

3. The process of making a one piece railroad frog having an integral centrally projecting separator block at each end with its 85 sides shaped to snugly fit into the channels in the sides of the track rails, each block being of gradually increasing width from 90 its neck to its end; consisting in operating on a bar of substantially uniform cross sectional shape having a groove in its bottom extending from end to end and being not wider than one-third the width of the main 95 part of the frog, to widen the same at the region where the wings are to end, removing stock from the top of the bar to form the flangeways, wings and point, and operating on the end of the bar to form 100 said separator blocks.

4. The process of making a one piece railroad frog having an integral centrally projecting separator block at each end with its 105 sides shaped to snugly fit into the channels in the sides of the track rails, each block being of gradually increasing width from its neck to its end, consisting in operating on a bar of substantially uniform cross sectional shape and having a groove in its bottom 110 extending from end to end and being substantially not wider than one-fifth of the total width of the frog to widen the same at the region where the wings are to end, removing stock from the top of the bar to 115 form the flangeways, wings and point, and operating on the end of the bar to form said separator blocks.

In testimony whereof I affix my signature.
CHARLES AMES ALDEN.
